UNITED STATES PATENT OFFICE

JULIUS MUGLER, OF BERLIN, GERMANY

DOUBLE-JET CONTROL DEVICE

Application filed September 20, 1929, Serial No. 334,071, and in Germany July 3, 1928.

Single jet control devices for measuring apparatus and regulators are known in which the fluid jet is controlled by an impulse-influenced, movable pipe. Double jet control devices are also known in which fluid jets are discharged from a stationary member and are supplied through an impulse-actuated double slider having co-axial apertures over a free space to two opposite offset stationary apertures. In contrast thereto according to the present invention a double jet control device is provided in which two jets discharged from a stationary pipe are received directly by an impulse-operated fork provided with offset openings and are supplied through the movable fork to the measuring apparatus or servo-motor of a regulator.

This control device has therefore the advantages of a double jet control device, but eliminates the diminution of the jet through the openings of the slide valve and the free space which has to be bridged in the known double jet control device.

25 The new double jet control device is illustrated in the accompanying drawing in combination with a servo motor,

Figure 1 is a side elevation partly in section.

30 Figure 2 is a diagrammatic plan view, and

Figure 3 is a sectional elevation on the line 3—3.

The operative fluid or liquid which enters at 1 is discharged through outlets 2 and 3 in two streams or jets. Opposite these outlets 2 and 3 are located the off-set receptor openings 5 and 6 provided in a fork 4. Two channels 7 and 8 extend through the fork 4 from these openings to the fulcrums 9 and 10 of the fork. At these points pipes 11 and 12 are connected to the fulcrum ends of the channel and serve for conducting the fluid admitted through the openings 5 and 6 to the servo motor, for example to both 45 sides of a piston 13. 14 is the device which produces the impulses and comprises as shown for example a membrane acted upon by the pressure of the medium to be regulated through the impulse pipe 15. The deflections of this membrane produced by the

55 pressure variations of the medium to be regulated are transmitted to the fork 4, for example, by a plunger 16. A weight, or as illustrated, a spring 17 acts as a counter-weight to the pressure acting on the membrane. By adjusting the spring 17 the pressure which for example is to be maintained constant by the control device may be adjusted to a predetermined degree.

60 The operation is as follows:—

The pressure variation of the medium to be regulated, for example, the pressure variation in a steam pipe 18, is transmitted through the impulse pipe 15 to the membrane 14. This becomes deformed and accordingly rocks the fork 4. If the fork is rocked for example so that the opening 5 therein registers with the outlet 2, the pressure fluid discharged from the latter enters the opening 5 and is conducted through channel 7 to the side 19 of piston 13. The outlet 6 on the other hand is freed and the fluid on the opposite side 20 of the piston passes through pipe 12 and channel 8 out through the opening 6. The piston 13 is moved upwards and controls the regulating member, for example, throttle valve 11, until the desired pressure is restored in the pipe 18. Thereupon the fork 4 is also returned to an intermediate position, that is to a position in which the 70 openings 5 and 6 are simultaneously in part registration with the outlets 2 and 3 so that both the sides 19 and 20 of the piston are acted upon by the same pressure with the result that the piston remains in the rest position until a new impulse is produced by further variation in pressure.

80 By making the member from which the two jets 2 and 3 are discharged movable in the same direction as the fork and by making this displacement in proportional dependence, for example, upon movement of the piston 13 in such a manner that the jet member always follows the movement of the fork, a double jet control device is obtained 85 having a progressive action.

Claims:

1. A double jet control device comprising a rockable member having means thereon providing a pair of oppositely directed recep-

- tor openings, means to direct currents of fluid into said openings and including a pair of jet openings each of which is adapted to cooperate with a respective receptor opening, the openings of one of said pairs being offset with regard to one another so that a movement of said member in either direction causes one receptor opening relatively to approach its corresponding jet opening and the other receptor opening to move away from its jet opening or vice versa, and a device operated by differential fluid pressures and including a movable element exposed on the one hand to the fluid pressure existing at one receptor opening and on the other hand to the fluid pressure existing at the other receptor opening.
2. A double jet control device comprising a fork, having two receptor openings directed toward one another and offset from one another, means for providing a pair of aligned jet outlets directed away from one another and adapted each to cooperate with a receptor opening, means to move said fork so that upon movement in one direction one of the said outlets is brought toward alignment with its receptor opening and the other jet opening is moved away from its receptor opening, and vice versa upon movement in the other direction, and a device operated by differential fluid pressures and including a movable element, and means to impose upon one side of said element the fluid pressure existing at one receptor opening and on the other side of said element the fluid pressure existing at the receptor opening.

In testimony whereof I have signed my name to this specification.

JULIUS MUGLER.
